UNITED STATES PATENT OFFICE.

ARTHUR S. TREW, OF PORTLAND, OREGON, ASSIGNOR TO TREW TABULATING MACHINE COMPANY, A CORPORATION OF OREGON.

PNEUMATIC CARD-DISTRIBUTING MACHINE.

1,333,193.

Specification of Letters Patent. Patented Mar. 9, 1920.

Application filed November 29, 1915. Serial No. 64,050.

To all whom it may concern:

Be it known that I, ARTHUR S. TREW, a citizen of the United States, residing in the city of Portland, county of Multnomah, and

5 State of Oregon, have invented certain new and useful Improvements in Pneumatic Card-Distributing Machines, of which the following is a specification.

My invention relates to card distributing 10 machines of the general character referred to in my pending application, filed February 4, 1915, Serial Number 6,159. The broad object of my invention is to provide practical machines for rapidly and accurately assorting 15 and distributing cards, tickets, and the like, from a container into a series of receiving pockets, or receptacles. To do this rapidly and accurately, without providing specially prepared cards, requires that the 20 cards in the container be so supported that the foremost card, or the one to be next ejected, must be exposed to the view of the operator, in order that the operator may see from the card itself, at a glance and before 25 the card starts on its way, into which receptacle the card should go. The mechanism must also be direct acting, with means for manually controlling the same, as by means 30 of a key, lever, or the like, with such connections therefrom to the ejecting mechanism and the distributing mechanism that the instant the key, or lever, is depressed, or moved, the card is ejected from the container 35 and deposited in the proper pocket.

35 The main object of the present improvements in such distributing machines is to provide therein pneumatically operated mechanisms, that is, ejector and switch members, which are pneumatically operated, 40 with a manual control. In order that others may clearly understand my invention, I have illustrated one practical embodiment thereof in the accompanying two sheets of drawings which I will now describe.

45 Figure 1 is a top plan view of a pneumatic card distributing machine embodying my invention;

Fig. 2 is a vertical longitudinal sectional view taken on the line 2—2 of Fig. 1;

50 Fig. 3 is a horizontal longitudinal sectional view taken on the line 3—3 of Fig. 2;

Fig. 4 is a vertical sectional view taken on the line 4—4 of Fig. 2;

Fig. 5 is a similar view taken on the line 5—5 of Fig. 2;

55

Fig. 6 is an enlarged sectional view, taken on line 6—6 of Fig. 1, showing controlling keys with their operating connections for controlling the air valves;

Fig. 7 is a fragmentary perspective view 60 of one of the switch members with parts broken away;

Fig. 8 is a plan view of a detail;

Fig. 9 is a sectional view, on line 9—9, 65 Fig. 7, through one of the switch members;

Fig. 10 is an enlarged view of one of the operating plungers; and

Fig. 11 is a detail view of a spring-pressed feed roller.

Referring now more in detail to the drawings, the present embodiment of the invention comprises a table-like structure having the legs 1—1, a lower supporting shelf 2, an intermediate supporting shelf 3, and a top 4. Formed on the top 4, toward the left hand end thereof, is a transversely extending depressed trackway 5, upon which is mounted to travel a card carriage 6, adapted to receive a supply of cards 7, said carriage having a back wall 8, with a spring bumper-like member 8^a, against which the cards rest. Said card carriage has attached thereto a cable 9, passing thereunder, and over a pulley 10, mounted in a supporting member 11. Said cable has attached to its lower end 85 a weight 12, which operates to gradually move the card carriage forwardly on the trackway 5, as the cards are ejected from the front thereof one by one.

Mounted in front of said card carriage is 90 a fixed glass front 13, against which the foremost card rests as the card carriage is moved forwardly by the weight 12, said glass front being such as will expose the face of the front card to view, and being positioned 95 so that the floor of the card carriage will move thereunder as the carriage is moved forwardly on the trackway 5, by the weight 12, as clearly indicated in Fig. 4.

Mounted to reciprocate immediately in the 100 rear of the glass front 13, is an ejector 14, in the supporting members 15—15, said ejector

being operated by a lever 16, pivotally mounted as at 17, upon the intermediate shelf 3, and having its lower end projecting downwardly, as at 18, for connection with operating mechanism hereinafter described.

Arranged upon the top 4, Fig. 1, are a plurality of receiving pockets, there being three shown in the drawings for purposes of illustration, and designated 19, 20 and 21, said pockets having slots 19^a, 20^a and 21^a, in their bottoms with inclined track members, as 19^b, 20^b and 21^b, shown in dotted lines in Fig. 1, and more clearly indicated in Fig. 5. Mounted upon said inclined trackways and operating through the respective slots in the bottoms of the receptacles, or pockets, are follower members 22, 22' and 22'', said follower members being provided with follower plates, as 23, 23' and 23'', set at a slight angle within the pockets, or receptacles, as clearly indicated in Fig. 1, for a purpose hereinafter again referred to. Mounted upon the top 4, along the front of the receiving pockets, is a wall member 24, extending from the side of the card carriage to form a passageway from the front of said card carriage along adjacent the entrances of the different pockets, or receptacles.

Mounted in the front of each of the pockets, or receptacles, is a switch member, clearly shown in Fig. 7, and comprising a plate 25, hingedly mounted at one end, in a suitable bracket, as 26, upon a pivoted pin 26^a, upon which pivoted pin is mounted a spring 27, adapted to press against one end of the plate 25, as at 28, to normally hold the opposite end of the plate 25, spaced away from the back wall 24, as indicated in full lines of Fig. 9. Mounted upon each of the plate members 25, is a pair of guide members 25^a, adapted to direct the cards from the passageway in front of the wall member 24, into the respective pockets, when anyone of the switch members 25, is moved outwardly at its free end across the passageway and against the back wall member 24, as indicated in dotted lines, Fig. 9, and as shown in connection with pocket 21, in Fig. 1.

As a means for gripping and forcing the cards ejected from the side of the card carriage along the passageway between the wall member 24, and switch plates 25, I have provided a series of rollers, which I will now describe.

Next adjacent the front and at one side of the card carriage, in position to grip the end of each card, or ticket, as it is ejected therefrom by the ejector 14, is yieldingly mounted, with their engaging peripheries in the passageway, a pair of small rollers 29, adapted to be spring-pressed against a corresponding pair of larger disk-like rollers 30, as clearly indicated in Figs. 1, and 11. The larger rollers 30, are mounted

upon the upper end of a shaft 31, having bearings in the top 4, and the intermediate shelf 3, as clearly indicated in Fig. 2, and being provided with a belt pulley 32, at its lower end, immediately underneath the intermediate shelf 3. Mounted adjacent the entrances to the pockets, or receptacles, are large rollers 33, 33' and 33'', upon shafts 34, 34' and 34'', with co-operating small rollers 35, 35' and 35'', as clearly indicated in Fig. 1. The shafts 34, 34' and 34'', upon which the larger rollers 33, 33' and 33'', are mounted, have bearings in the top 4, and in the intermediate shelf 3, as clearly indicated in Figs. 2, 4 and 5. The shafts 34' and 34'', are provided between the top 4, and the intermediate shelf 3, with gears 36-36'. The small rollers 35, 35' and 35'', are mounted upon crank-like members 37, 37' and 37'', mounted upon the upper ends 85 of shafts 38, 38' and 38'', which are provided at their lower ends with coiled springs, as 39, operating to normally hold the small rollers 35, 35' and 35'', in yielding engagement with the larger rollers 33, 33' and 33''. Also mounted through the top, with bearings in said top 4, and intermediate shelf 3, are shafts 40, 40' and 40'', having mounted upon their upper ends in the entrances to the pockets, or receptacles, 19, 20 and 21, beater members 41, 41' and 41'', adapted to beat the cards, or tickets, back against the follower plates 23, 23' and 23'', as said cards are discharged into said pockets. Said shafts 40, 40' and 40'', are provided, between the top 4 and the shelf 3, with gears 42, 42' and 42''. The shaft 40' is provided at its lower end with a belt pulley 43, as indicated in Fig. 2.

The feed rollers 33, 33' and 33'', and the beater members 40, 40' and 40'', are driven together in the proper directions by means of belts and intermeshing gears, which I will now describe. A belt 44, passes around a drive pulley 45, thence up over a guide pulley 46, thence around the pulley 32, on the lower end of a shaft 31, which carries feed rollers 30, at its upper end. Said belt then passes against a pulley 47, Fig. 3, upon the lower end of a shaft 34, which carries feed roller 33, at its upper end; thence around a pulley 48, upon the lower end of a shaft 49, mounted between the top 4, and the shelf 3; thence to and around pulley 43, upon the lower end of a shaft 40', which drives the beater 41'; thence to and around a pulley 50, mounted upon the lower end of a shaft 51, mounted between the top 4, and the shelf 3, and directly behind the shaft 40'', in Fig. 2. Said belt next passes around a guide pulley 52, supported from the under side of the shelf 3; and thence over a guide pulley 53, and back to the driving pulley 45.

The driving pulley 45, is mounted upon a 130

- shaft 54, supported in bearing standards 55, upon the lower shelf 2, said shaft 54, being driven by means of a pulley 56, and a belt 57, from a motor pulley 58, of a motor 59. 5 Thus the feed rollers 30, are driven by the belt 44, around its pulley 32. The feed roller 33, is also driven by the belt passing against its pulley 47. The first beater 41, is driven through the gear 42, mounted on 10 its shaft 40, and in mesh with a gear 60, mounted upon the shaft 49, which is driven by the belt passing around its pulley 48. The feed roller 33', upon the shaft 34', is driven through the gear 36, which meshes 15 with the gear 60, upon the shaft 49. The beater 41', upon the upper end of said shaft 40', is driven by the belt around its pulley 43. From the gear 42', on the same shaft 40', is driven an idle gear 61, interposed 20 between the gear 42' and the gear 36', the latter of which is mounted upon the shaft 34'', upon the upper end of which is mounted feed roller 33''. The beater 41'', mounted upon the upper end of the shaft 40'', 25 is driven by the gear 42'', mounted upon the same shaft, and in mesh with a gear 62, upon the shaft 51, which is driven by the pulley 50. These driving connections can be followed by reference to Figs. 1, 2 and 3. 30 I will next describe the pneumatic mechanism by means of which the ejector 14, and the switch members 25, 25' and 25'', are operated from a common keyboard.
- Mounted upon the lower shelf 2, is an air 35 compressor 65, driven by a belt 66, running over a driving pulley 67, mounted upon the shaft 54, and driven from the motor 59, by the belt 57, as hereinbefore described. Said compressor is connected by means of a pipe 40 68, to a reservoir 69, in which air under pressure is stored. From this reservoir leads a supply pipe 70, which connects with the under side of an air box 71, as indicated in Figs. 2, 3, 4 and 6. Said air box 71, is 45 provided near one end with a partition 72, having a valve controlled opening therethrough with a valve 73, seated therein, said valve being operated by means of a rod 74, which is also provided with a valve 75, 50 adapted to close an outlet, or exhaust opening 76, in the end of said air box. The valve member 73, is held normally closed by means of a coiled spring 77, mounted in a casing 78, upon the partition 72, as clearly indicated in Fig. 6. From the end of the air 55 box, which is partitioned off by the partition 72, is an air pipe 79, extended to the lower end 18, of the ejector lever 16, as indicated in Figs. 2 and 3, said pipe being provided 60 in its end with a plunger 80, Fig. 10, adapted to be forced outwardly by air admitted to said pipe 79, for operating said ejector lever 16, and by means of which the ejector 14, is actuated for ejecting the foremost card 65 from the card carriage 8. A spring 81, con-
- nected at one end to the lower end 18, of said ejector lever 16, and at its other end to a fixed member 82, operates to normally return said ejector lever 16, and the ejector 14, to their normal, or inoperating, positions. 70
- Referring now to Fig. 6, I will describe the key control of the air supply from said air box 71, to the different switch and ejector operating mechanisms.
- Fig. 6 is a vertical, sectional view on line 75 6-6 of Fig. 1. The air box 71, is mounted beneath the intermediate shelf 3, while a key box, or casing, 83, is mounted on top of said intermediate shelf, or casing, as indicated in Figs. 1, 4 and 6. Slidably mounted 80 within said key casing 83, is a key-holding plate 84, suitably supported upon posts 85-85, and provided with a spring 86, attached thereto at one end, and at its other end attached to the inner side of 85 the key casing, as indicated in Fig. 6, for the purpose of holding said key-holding plate 84, in its normal position. Mounted through said key casing, are a plurality of operating keys 87, 88, 89 and 90, 90 said keys being provided on the under side of the top of said key casing with shoulder portions 87^a, 88^a and 89^a, adapted to engage the top of said key casing, and thereby to limit the upward movement of said keys, 95 said shoulder portions being curved into cam surfaces at their under sides, as at 87^b, 88^b and 89^b, whereby as anyone of said mentioned keys is depressed, it will operate through its cam portion to move the holding plate 84, longitudinally within the key casing and in doing so will operate a rocker lever 91, pivotally connected to the under side thereof, as at 92, and at its lower end connected to the valve rod 74, in the end of 100 the air box 71. Thus the movement of anyone of the keys last mentioned, operates to open the valve member 73, and close the valve 75, in the air box 71, to admit air into the end portion of said air box and through 105 the pipe 79, leading to the operating plunger 80, Fig. 10, which actuates the ejector 14. The keys 87, 88 and 89, are also provided at the opposite sides of their stems with small shoulders as 87^c, 88^c and 89^c, which operate 110 to prevent any of the keys being depressed while one key is down. This will be evident from the drawing, as shown in Fig. 6. Each of the key stems is provided underneath the holding plate 84, with coiled springs as 87^d, 88^d and 90^d, which operate to normally hold 115 said keys in their raised, or normal positions, in a manner which is clear from Fig. 6, of the drawings. Certain of said key stems, at their lower ends, are connected 120 with valve members for controlling air passageways from the air box 71, as follows:
- Key 87 operates a valve 93, in a valve casing 94, mounted upon the air box 71, and connected with an air pipe 95, extending to 130

the first switch member 25, in the card receptacle 19, as will be understood by reference to Figs. 1 and 6. Key 88 is connected at its lower end to a valve member 96, in a valve casing 97, mounted upon said air box 71, and having connected thereto a pipe 98, which extends to the switch 25', in the entrance of card receptacle 20, and the lower end of key 89, is connected to operate a valve member 99, in a valve casing 100, mounted upon said air box 71, and having connected thereto a pipe 101, extended to the switch member 25'', in the entrance of receiving pocket 21. It will be understood, of course, that the switch ends of the pipes 95, 98 and 101, are provided with a plunger, as shown in Fig. 10, adapted to engage and move the switch members 25, 25' and 25'', when air is admitted to their respective pipes by the operation of their respective keys, the plunger in pipe 101, being shown in Fig. 1, to be extended in position to open the switch member 25''. It is also to be noted that the curved cam surfaces 87^b, 88^b and 89^b, of the key stems 87, 88 and 89, terminate at their upper ends in little shoulders on the right hand side of the key stems, as shown in Fig. 6, and below the shoulders 87^a, 88^a and 89^a, which shoulders catch under the plate 84, when anyone of said keys is depressed, and in order to be released, the plate 24, must be slightly shifted to the right.

I will next describe two methods of doing this.

35 Key 90 is a release key only, and is provided with a member 90^a, having an inclined end of such character that when the plate 84, is shifted to the right, if said key 90 is depressed, its member 90^a, will engage and move said plate 84, sufficiently farther to the right to release the depressed key. However, I have provided automatic means, controlled by the passing of a card for shifting said plate 84, sufficiently to release the key 40 immediately after each card passes its switch member. From the top of the reservoir 69, is a pipe 102, as shown in Figs. 2 and 3, which extends along underneath the top 4 and the several switch members, shown on 45 an enlarged scale in Figs. 7 and 8, and at each switch member said pipe 102, is provided with a short branch pipe 103, constituting a valve casing with a valve member 104, moving therein, and adapted to be operated by means of a lever 105, attached to the lower end of a rod 106, rotatably supported at its upper end in a bearing plate 107, mounted upon the upper end of the back wall 24. Mounted upon said rod 106, is an 50 operating prong-like member 108, which projects through the guide member 25^a, on each of the switch plates 25, in a position to be engaged by a card passing along said guide members 25^a, when said switch mem-

ber is in the position shown in dotted lines 65 in Fig. 9. As the card engages this prong member 108, which is secured to the rod 106, it operates said prong member, so as to turn said rod 106, and to move the little lever 105, inwardly, so as to press the valve member 104, inwardly, to open air communication from the pipe 102, to a return pipe 109, which terminates adjacent the operating lever 91, near the controlling box, as indicated in Figs. 3 and 6, and is provided with 70 a plunger, similar to the plunger 80, shown in Fig. 10, for moving said lever 91, so as to further shift the holding plate 84, to automatically release any of the keys which may be down, in the manner which will be clearly 75 understood from Fig. 6 of the drawings. A spring 110, Fig. 8, operates to hold the little lever 105, on the rod 106, which carries the card tripping prong 108, in its normal 80 position.

85 The operation of the machine may be briefly described as follows:

Assuming that the motor 59, is running, the belt 44, and the several intermeshing gears, are driving the feed rollers 30—29, 90 33, 33' and 33'', and the beaters 41, 41' and 41'', the small rollers 35, 35' and 35'', being held in yielding engagement with the larger feed rollers 33, 33' and 33'', are driven 95 thereby. The cards, or tickets, to be distributed have been placed in the carriage 8, in the manner clearly indicated in Fig. 1. The pressing of the first key 87, for example, operates to shift the key plate 84, rocking the lever 91, so as to open the valve 73, and 100 close valve 75, in the air box 71, whereby to admit air to the pipe 79, which is provided in its end with the plunger 80, which operates the ejector lever 16, and the ejector 14, which engages the front, or foremost card in 105 the container, immediately behind the glass front 13, ejecting said card, or ticket, sufficiently for it to be engaged by the rollers 30—29, which pass it on to the other rollers 33—35. The pressing of the key 87, also 110 simultaneously moves the valve member 93, downwardly so as to close the upper end of the valve casing 94, and at the same time open communication between the pipe 95, and the air box 71. As said pipe 95, is 115 extended to the first switch member 25, and has a plunger in its end, similar to the plunger construction shown in Fig. 10, it will be evident that said switch member 25, will be moved across the passageway leading 120 from the card carriage so that the first card will be directed into the first pocket, or receptacle, 19, the beater 41 therein beating it back against the diagonally positioned gravity follower 23. As said card passes 125 along the guide members 25^a and into said first pocket, shown more clearly in Figs. 7 and 9, it strikes the prong 108, and momen-

tarily opens the valve 104, in the valve casting 103, which connects the pipe 102, from the air reservoir with the return pipe 109, thus admitting air pressure from the reservoir to said pipe 109, which operates its plunger against the lever 91, Fig. 6, sufficiently to move the key plate 84, for the purpose of releasing the key 87, which, when pressed down, was held down by reason of the engagement of its shoulder with said key plate 84, as hereinbefore described. Thus with the operation of any one of the keys 87, 88 or 89, the valve 73, is opened to pass air under pressure to the plunger which operates the ejector and at the same time air under pressure is admitted to the pipe leading to the switch member corresponding to the particular key depressed.

I am aware that many changes in the details of the mechanism here shown for the purpose of illustrating my invention can be made without departing from the spirit thereof, and I do not, therefore, limit the invention to these details, except as I may be limited by the hereto appended claims.

I claim:

1. In a card distributing machine, in combination, a card container, an ejector operating therein and adapted to eject the cards therefrom one by one, a receptacle for said cards, a switch controlling the entrance to said receptacle, a source of air under pressure, and manually controlled means for pneumatically and simultaneously operating said ejector and said switch member.

2. In a card distributing machine, in combination, a container for cards, an ejector operable therein, a series of card receiving pockets with a card passageway formed from said container along said pockets, means for conveying said cards along said passageway, switch members for said card receiving pockets adapted to be moved across said passageway to direct the cards into said pockets, a series of keys corresponding to said pockets, a source of air under pressure, and pneumatically operated means, controlled by said keys, adapted to operate said ejector and the switch member to the pocket corresponding to the key operated.

3. In a machine of the character referred to, a card container, a reciprocating ejector operable therein and adapted to engage and eject cards edgewise therefrom one by one, a source of air under pressure, an air operated plunger, operating connections from said plunger for operating said ejector, and means for controlling the movement of said plunger.

4. In a card distributing machine, a support for the cards, a pneumatic ejector adapted to engage the cards edgewise one by one and to eject the same, receivers for the cards, switches for deflecting the cards into

the desired receivers, and key-controlled means adapted to operate said pneumatic ejector, and to set the desired switch.

5. In a machine of the character described, a card container adapted to hold a series of cards in edgewise position, a pneumatically operated ejector mounted to eject said cards one by one in a horizontal direction, means for manually controlling said pneumatically operated ejector, in combination with a series of distributing pockets, and switches to deflect the cards to their appropriate pockets, said switches being connected to be also actuated by said manually-controlled means.

6. In a machine of the character described, a card container adapted to hold the cards to be distributed, a pneumatically operated ejector, adapted to engage the cards edgewise individually for ejecting the same from said container, a plurality of distributing pockets, switches adapted to deflect the cards to their appropriate pockets, pneumatic means for operating said switches, and a series of keys with operating connections from each for operating said pneumatic ejector, and one of said pneumatically operated switches.

7. In a machine of the character described, a container for the cards to be distributed, a pneumatically operated ejector, pneumatically-controlled distributing means, and selective manually operable devices for simultaneously causing the ejection of a card and determining its place of distribution.

8. In a machine of the character referred to, in combination, a card container, a series of receiving pockets with a passageway formed thereto from said container, means for conveying cards from said container along said passageway, pneumatically operated means for directing cards from said passageway into said several pockets, a pneumatically operated ejector adapted to engage and eject said cards edgewise, one by one, from said container into said passageway, and manually controlled means for simultaneously causing the actuation of said pneumatically operated ejector and said pneumatically operated means for deflecting cards from said passageway into selected pockets.

9. In a machine of the character referred to, in combination, a container for cards, a series of pockets with a passageway thereto from said container, means for conveying cards along said passageway, a pneumatically operated ejector adapted to engage and eject cards, one by one, from said container into said passageway, pneumatically operated switches for deflecting cards from said passageway to said several pockets, manually-controlled means for simultaneously causing the actuation of said ejector and

- 6
- one of said switch members, and means adapted to be engaged by a card entering a pocket for automatically restoring said manually-controlled means to normal position.
- 5 10. In a machine of the character referred to, in combination, a card container, a plurality of card receptacles, pneumatically operated mechanism for simultaneously ejecting a card and determining its place of distribution, means for manually controlling the same, and means adapted to be engaged and actuated by a card entering one of said receptacles for restoring said pneumatically operated mechanism to its normal condition.
- 10 11. In a card distributing machine, in combination, a card container, a series of receiving pockets with a passageway thereto from said container, pneumatically operated switch members for said pockets adapted to be moved across said passageway, a pneumatically operated ejector adapted to eject cards edgewise into said passageway, means for passing said cards along said passageway, manually operable means for causing 25 the simultaneous operation of said ejector and one of said switch members, and means positioned to be engaged by a card passing into one of said pockets for causing the automatic restoration of said pneumatically 30 operated mechanism to its normal condition, substantially as described.
12. In a card distributing machine, in combination, a card container, a pneumati-
- cally operated ejector therefor, a plurality of receiving pockets for said cards, means 35 for conveying said cards from said container to said pockets, pneumatically controlled selective mechanisms for determining which pocket receives an ejected card, a source of air under pressure with air pipes 40 to said ejector and to said selective mechanisms, and manually controlled means for causing the operation of said ejector and said selective mechanism at will.
13. In a machine of the character described, in combination, a card container, an ejector operable therein for ejecting cards one by one, a series of receiving pockets, means forming a passageway from said container along said pockets, switch members in said pockets adapted to be moved across said passageway to deflect cards therefrom into said pockets, means for pneumatically operating said switch members, and manually operable means for causing 55 the simultaneous operation of said ejector and one of said switch members, whereby to eject a card and to cause its deposit in a selected pocket.

Signed at Portland, Multnomah county, 60
Oregon, this 20th day of November, 1915.

ARTHUR S. TREW.

In presence of—

I. M. GRIFFIN,
W. C. CLAUSSSEN.
